CLAIM

The ornamental design for an coffee grinder, as shown and described.

DESCRIPTION

FIG. 1 is a front, right-side, and top view of a coffee grinder showing the new design.

FIG. 2 is a front elevation view of the coffee grinder.

FIG. 3 is a back elevation view of the coffee grinder.

FIG. 4 is a left-side elevation view of the coffee grinder.

FIG. 5 is a right-side elevation view of the coffee grinder.

FIG. 6 is a bottom plan view of the coffee grinder; and,

FIG. 7 is a top plan view of the coffee grinder.

Any portions of the coffee grinder that are not clearly disclosed form no part of the claimed design.
